UNITED STATES PATENT OFFICE

164,435

EXHAUST VENTILATING FAN UNIT

William Jack Lovelace, Indianapolis, Ind.

Application September 15, 1950, Serial No. 12,204

Term of patent 14 years

(Cl. D62—4)

To all whom it may concern:

Be it known that I, William Jack Lovelace, a citizen of the United States, residing at Indianapolis, in the county of Marion and State of Indiana, have invented a new, original, and ornamental Design for an Exhaust Ventilating Fan Unit, of which the following is a specification.

Fig. 1 is an end elevational view of an exhaust ventilating fan unit embodying my new design and showing the outer end thereof;

Fig. 2 is a side elevational view thereof;

Fig. 3 is an end elevational view of the inner end thereof; and

Fig. 4 is a bottom plan view thereof.

I claim:

The ornamental design for an exhaust ventilating fan unit, as shown.

WILLIAM JACK LOVELACE.
